LEASH CHAIN WITH WRIST CLIPS

Willie F. Thompson, 2528 Highland St.,
Kansas City, Mo. 64108

Filed July 7, 1969, Ser. No. 18,080

Term of patent 14 years

Int. Cl. D2—99

U.S. Cl. D2—452

FIGURE 1.

FIGURE 2.

FIGURE 3.

FIGURE 4.

FIGURE 5.

FIGURE 6.

FIG. 1 is a plan view of a leash chain with wrist clips, showing my new design;

FIG. 2 is a side elevation thereof;

FIGS. 3 and 4 show the opposite view of FIG. 1 with the leash chain omitted; and

FIGS. 5 and 6 show an opposite elevation of FIG. 2 with the leash chain omitted.

I claim:

The ornamental design for a leash chain with wrist clips, as shown.
